SCRAPER

Frank Elliott, Oakland, Calif.

Application August 10, 1939, Serial No. 289,333

3 Claims. (Cl. 30—169)

This invention relates to tools in the nature of handles for holding blades used for cutting or scraping purposes and particularly to those designed for use with discarded safety razor blades.

It is an object of the invention to provide an improved utility tool using safety razor blades.

Another object of the invention is to provide, in a tool of the character described, means for automatically sheathing the razor blade during periods when the tool is not in use so that persons may not be accidentally cut by coming in contact with the tool and the cutting of clothing is prevented if the tool should be carried in the pockets thereof.

A further object of the invention is to provide, in a tool of the class described, means which facilitates removal or replacement of the blade without the necessity of removing screws or other such attachment parts.

The invention possesses other objects and features of advantage, some of which, together with the foregoing, will be specifically set forth in the detailed description of the invention hereunto annexed. It is to be understood that the invention is not to be limited to the specific form thereof herein shown and described as various other embodiments thereof may be employed within the scope of the appended claims.

Referring to the drawing:

Figure 1 is a front elevational view of the tool of my invention. A portion of the view is broken away so as to more clearly disclose the interior construction.

Figure 2 is a side elevational view of the structure illustrated in Figure 1.

Figure 3 is a vertical sectional view of the tool. The plane in which the view is taken is indicated by the line 3—3 of Figure 1.

Figure 4 is a front elevational view, similar to Figure 1, showing the blade in projected position and the relative positions of other parts of the structure. Portions of the view are broken away to shorten it.

Figure 5 is a perspective view of the blade carrier. A portion of the view is broken away so as to disclose the construction more clearly.

There is on the market, at the present time, a large variety of tools of the scraper class which are designed to use, as cutter blades, safety razor blades that have become too dull for shaving purposes. The large majority of these scraper tools provide a clamp so that the razor blade may be fixedly mounted on and to project from an extending handle. After being used to per-

form a cutting or scraping job, these tools are usually laid down on a nearby shelf or bench or may be placed in a drawer until they are needed again. If persons forget, or are not warned of, the presence of the tool in its storage place and carelessly pass their hands over the surfaces or into the drawer where the tool is kept they are very likely to suffer severe cuts due to their hands brushing against the exposed razor blade. Some manufacturers of these tools, recognizing this danger, have provided means whereby, after the tool has been used, the razor blade may be moved into the clamp to a position where portions of the clamp will cover the sharp edge of the blade and effectively protect persons against being cut thereby. Usually this protection feature consists of one section of the two-piece blade clamp which may, upon loosening of one or more screws or nuts, be shifted to a position overlying the blade edge. Provision of such a device does not however render the tool absolutely safe since there is nothing to prevent a careless user from putting it away without bothering to set the blade shield. I have provided an improved tool of the character described which, as soon as the tool is set down after use, operates automatically to retract the blade so that its sharp cutting edge will not be exposed.

In detail the tool comprises a head 6 having a rectangular passage 7 extending vertically therethrough, a pair of ears 8 projecting from the opposite vertical ends thereof, and downwardly projecting arms 9, the confronting inner surfaces 11 of which are alined and coextensive with the vertical end surfaces of the passage 7. Disposed in the passage 7 and movable axially thereof is a blade carrier, best shown in Figure 5, comprising a base 12, whose length is slightly less than the distance between the surfaces 11 so that the base may slidably pass therebetween, having in a longitudinal side thereof a pair of parallel grooves 13 which diverge downwardly with respect to each other and are each slightly wider at the bottom than at the top as is probably best shown in Figure 3. Associated with the base 12 is a pair of sheet metal chuckplates 14 each having along a longitudinal edge thereof an angularly disposed flange 16 which enters a groove 13. One of the plates 14 is provided with an elongated slot 17 and the other plate has therein a corresponding embossed ridge 18 which may enter the slot 17 when the plates are brought together. A safety razor blade 19 is placed between the plates 14, the latter being then brought together so that the ridge 18 not only passes into

the slot 17 but also through the elongated centering aperture 21 of the blade thus locking the blade in position between the plates. Since the grooves 13 are each wider at the bottom than at the top thereof, a small amount of movement of the plate flanges 16 is allowed therein thus permitting the plates to be moved apart about a pivot point, which lies in the plane of the top of the base 12, so that the blade 19 may be inserted or removed. The blade carrier, with a blade positioned between the plates 14, is placed in the head 6 with the plates 14 entering the passage 7, the combined thickness of the plates and blade being such that the plates may slide freely in the passage so as to project the blade from the upper open end of the passage as shown in Figure 4 or to retract the blade below the portions of the head bordering the end of the passage as shown in Figure 1 so that the sharp edge of the blade will be concealed.

Means is provided for moving the blade carrier between two extremes of movement so that the blade may be moved from concealed to exposed positions and vice versa. Formed in the ears 8 of the head 6 are apertures into which are pressed pivot pins 22 which project slightly at each end beyond the face of the head and on which are pivotally journaled the side flanges 23 of handles 24 that are pressed from sheet metal into U-shaped cross-sectional form. Each of the handles are provided with an integral extension lever 26 having at the distal end thereof a notch 27. The blade carrier base 12 has, projecting from opposite sides thereof, studs 28 with which the notched ends of the respective extension levers 26 are engaged. Each handle 24, adjacent its lower end, is provided with a pair of apertures 29 through which is threaded, so as to anchor it to the handle, one end of a leaf spring 31, the other end of the spring being slidably engaged in a slot 32 formed in the arm 9 of the head 6. When the handles 24 are squeezed together, as shown in Figure 4, the levers 26 will be swung upwardly thereby forcing the blade carrier upwardly in the passage 7 so as to project the blade 19 through the upper open end of the passage. This also flexes the springs 31. The springs are so designed that, upon release of the pressure squeezing the handles together, the springs will return to their unflexed positions, as shown in Figure 1, carrying with them the handles which will of course cause the blade carrier to be moved downwardly in the passage 7 so as to retract the blade 19. In the unflexed position of the springs the studs 28 remain in engagement with the notches 27.

A particularly desirable feature of the tool of my invention is that the blade may be removed for reversal or replacement without the necessity of removal of any screws, nuts or other such attachment parts. As will be best understood by reference to Figure 1, it will be seen that when the two handles 24 are spread apart the levers 26 will swing downwardly until the studs 28 pass outwardly from the ends of the notches 27 thus allowing the blade carrier to be dropped to the position indicated by the dotted lines 33. Reinsertion of the blade carrier, after the blade thereof has been reversed, so as to present a new cutting edge, or replaced, is just as simple, the carrier being placed in the tool with the plates 14

entering the passage 7 and the handles 24 being spread apart so as to permit the studs 28 to re-enter the notches 27.

It will be seen from the foregoing description that I have provided a tool, of the class utilizing safety razor blades, which automatically sheathes the blade immediately the tool is set down after being used so that the user's person or clothing are protected against cuts by coming into contact with the blade, and which makes changing or replacement of the blade a very simple task.

I claim:

1. A tool, of the type utilizing razor blades as cutters, comprising a head, a blade carrier separably engaging said head and movable relative thereto for moving a blade from a concealed position below a surface of said head to an exposed position beyond said surface, handles on said head manually engageable to move said blade carrier and said blade from concealed to exposed positions, said handles in a normal position of rest being in operative engagement with the blade carrier, and said handles upon movement thereof beyond said position of rest being released from engagement with said blade carrier.

2. A tool, of the type utilizing razor blades as cutters, comprising a head having a passage therein, a blade carrier, including a pair of chuck plates between which a razor blade may be engaged, slidably mounted in said passage to move a portion of said razor blade from a concealed position within said passage to an exposed position exteriorly of the passage, a pair of operating handles pivotally mounted on and extending from said head, said handles each being in releasable engagement with said blade carrier and being manually movable from a normal position of rest wherein said blade carrier and blade are in concealed position to a second position wherein said blade carrier and blade are moved to exposed position, and springs associated with each handle for returning said handles from said second position thereof to said position of rest thereof.

3. A tool, of the type utilizing razor blades as cutters, comprising a head having a passage therein and a pair of extension arms projecting from a side thereof and each provided with a surface coextensive with the respective end surfaces of said passage, a blade holder comprising a base extending longitudinally between and slidably engaging said arm surfaces, said base having in the top surface thereof a pair of parallel, downwardly diverging, grooves and studs projecting from opposite side surfaces thereof, a pair of chuck plates each having an angularly directed flange entering the respective base grooves, means on said chuck plates for securing therebetween a safety razor blade, said chuck plates being slidably engageable in said head passage, a pair of handles pivotally mounted on said head, arms carried by said handles each having a notch therein in which the studs of said base may be slidably engaged whereby, upon movement of said handles, said blade carrier and said blade may be moved along said passage, and springs associated with said handles, said springs, respectively, being engaged at one end with a handle and at the other end with said head.

FRANK ELLIOTT.
